CLAIM

The ornamental design for a bug zapper, as shown and described.

DESCRIPTION

FIG. 1 is a front perspective view of a bug zapper shown in a closed configuration, in accordance with our new design; FIG. 2 is a front elevation view thereof; FIG. 3 is a rear elevation view thereof; FIG. 4 is a right side view thereof; FIG. 5 is a left side view thereof; FIG. 6 is a top plan view thereof; FIG. 7 is a top plan view, with the handle shown removed; FIG. 8 is a bottom plan view of FIG. 1; FIG. 9 is an exploded perspective view of FIG. 1, in an unassembled configuration;

(Continued)

FIG. 10 is a front view thereof; and,
FIG. 11 is a perspective view, shown in a partially opened
configuration.

Any dashed broken line(s) in the drawings define unclaimed
subject matter that forms no part of the claimed design.
The broken line showing of the handle, the on/off switch and
bottom inner components is included for the purpose of
illustrating only and forms no part of the claimed design.
